[57] CLAIM

The ornamental design for a combined roasting pan and rack, substantially as shown.

DESCRIPTION

FIG. 1 is a perspective view of a combined roasting pan and rack showing our new design;

FIG. 2 is a side elevational view;

FIG. 3 is an end elevational view;

FIG. 4 is a top plan view;

FIG. 5 is a bottom plan view; and,

FIG. 6 is an enlarged cross-sectional view taken along lines 6—6 of FIG. 4.
